WINDOW REGULATOR

John H. Roethel, Detroit, Mich., assignor to Marvel Equipment Corporation, Detroit, Mich., a corporation of Michigan

Application November 16, 1939, Serial No. 304,814

2 Claims. (Cl. 268—126)

This invention relates to window regulators for raising and lowering glass or transparent panels or the like of vehicles, particularly automobile bodies, an object of the invention being to provide an improved window regulator which is relatively compact, light, positive and efficient in operation, relatively simple in construction and economical to manufacture, capable of being easily assembled in the body, and adapted to provide not only a desirable handle location but also to be utilized efficiently in connection with both narrow and wide window frames and doors.

A further object of the invention is to provide a window regulator having a main swinging or driving arm extending from a suitable fixed support or mounting plate and operated therefrom as by means of a driving gear, the regulator also comprising a second arm pivoted at one end to an intermediate point on the main arm, or to the outer end thereof as the case may be, and extending angularly therefrom in the direction of the mounting plate for connection to the lower edge of a window panel, a feature of the invention being the provision of positive means extending from the second arm, such as from the pivot thereof, toward the inner end of the main arm and operatively connected to the support for holding the second arm against pivotal movement independent of the main arm in any adjusted position of the panel while at the same time controlling the second arm so that it will swing in predetermined manner past the main arm as the window panel is raised and lowered.

A still further object of the invention is to provide a window regulator of the foregoing described kind in which link systems, levers and gears for controlling the second or balance arm from the mounting plate are eliminated, and a very simple, inexpensive, positive and light weight means is provided for this purpose in the form of an inextensible metal band, such as a steel tape, extending from the mounting plate over and fastened to a pulley or annular member secured to one end of the second or balance arm at the point where it is pivoted to the main arm. Preferably the steel tape is secured to the mounting plate at vertically spaced points and is adapted to be partially wrapped over an arcuate surface of the plate whose theoretical diameter is in such predetermined ratio to the diameter of the pulley that the balance arm will be swung in predetermined manner while at the same time locked or held against pivotal movement independent of the main arm in any adjusted position of the latter.

5 A further object of the invention is to provide a new window regulator of the two arm type which will support the window panel at spaced points, in which the two arms are positively controlled in improved manner and mounted compactly upon a single support or mounting plate whereby installation is facilitated and the window panel held substantially level against any material tilting in its plane during operation.

10 Other objects of this invention will appear in the following description and appended claims, reference being had to the accompanying drawings forming a part of this specification wherein like reference characters designate corresponding parts in the several views.

Fig. 1 is a fragmentary inner side elevation of an automobile door having installed therein a window regulator embodying the present invention.

15 Fig. 2 is a fragmentary side view of the window regulator in the fully raised position of the window panel.

Fig. 3 is an enlarged section taken substantially through lines 3—3 of Fig. 2 looking in the direction of the arrows.

20 Fig. 4 is a view, somewhat similar to Fig. 2, but illustrating the position of the window regulator in the half way position of the window panel.

Fig. 5 is a somewhat similar view illustrating the position of the window regulator when the window panel is fully lowered.

25 Fig. 6 is a view, somewhat similar to Fig. 2, but illustrating a second embodiment as applied either to a single arm or a two arm level travel regulator.

30 Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

35 Referring to the drawings, wherein I have illustrated, by way of example, embodiments of the present invention constructed and adapted for the purpose of raising and lowering a window panel of an automobile body, there is shown at D a door of an automobile body comprising a door frame 10 of any suitable construction formed with a main window opening. In the present 40 instance this window opening is closed by means

of a vertically slideable glass or other transparent panel 11. It will be understood that the present regulator may be utilized for the purpose of raising and lowering any of the window panels of an automobile body and in addition may be used generally in connection with various window structures for the purpose of raising and lowering the window panels thereof.

The sliding window panel 11 is adapted to be guided in any suitable manner within the window frame through the medium, for example, of the usual glass run channels, and in addition may be guided within the well below the window opening such as by means of front and rear vertically extending channel guides 12 and 13 engaged by roller guide devices 14 secured to opposite ends of the glass retainer member or channel 15 which embraces the lower edge of the panel 11.

In the present instance the window regulator comprises a suitable fixed support or mounting plate 16 which may be stamped or pressed from a sheet metal blank and having suitable screw bosses 17 by which the mounting plate may be secured within the window well to the inner door or body panel. A driving gear 18 is rotatively mounted upon the plate 16, this gear being in the form of a sector having gear teeth 18a in meshing relation with a driving pinion mounted upon a handle shaft 19, this shaft being operated by the usual crank handle at the inner side of the door or body and embodying in its length a suitable friction clutch of any conventional type. The sector gear 18, as shown in Fig. 2, is secured to a pivot stud 20 journalled within the mounting plate 16. Secured to the pivot stud 20 and also riveted at 21 to the gear 18 is a swinging driving arm 22 adapted to be swung upwards and downwards upon turning the gear 18 about its pivotal axis at 20. The arm 22 carries at its outer end a transverse stud 23 slideable horizontally within a guide slot or guideway 24a in an angle bracket 24 secured, as by spot welding, to the bottom of the channel 15. Acting upon the driving arm 22 and the gear 18 is a spirally wound counterbalancing spring 25, the inner end of which is fastened in a slot or kerf in the end of the stud 20 and the outer end of which is connected to a lug 26 struck out from the mounting plate.

As shown particularly in Figs. 1 to 5 inclusive the present two arm regulator also comprises a second swinging arm 27, herein termed for convenience a balance arm when utilized in connection with the two arm regulator. The arm 27 is shorter than the driving arm 22 and extends in overlapping relation thereto, the balance arm lying at all times at one side of the driving arm but adapted to pass the same during operation of the window regulator. The arm 27 is pivoted in overlapping relation to the driving arm through the medium of a pivot stud 28 riveted to the arm 27 and journalled in the arm 22, see Fig. 3. The outer end of the arm 27 carries a transverse stud 29 pivotally mounted within an aperture in an angle bracket 30 secured, as by spot welding, to the bottom of the channel member 15.

It will be seen that as the driving arm 22 of the two arm regulator is swung downwardly and upwards the pivot 28 of the shorter arm on the driving arm will move through an arc having its center at the axis 20 of the driving gear 18. For the purpose of imparting a compensating swinging motion to the arm 27 in a direction opposite to the swinging motion of the driving arm 22,

thereby causing the point of connection 29 of the shorter arm with the window panel to have the same or equal range of vertical travel as the point of connection 23 of the longer arm with the window panel, and at the same time to lock or hold the arm 27 against pivotal movement independent of the main arm in any adjusted position of the latter as well as the window panel, positive means extending from the second arm toward the inner end of the main arm 22 operatively connects the second arm with the support or mounting plate 16. Said means not only imparts the required swinging motion to the arm 27 but also positively locks it at any adjusted position of the window panel. Accordingly, there is fixedly secured to the pivot stud 28 of the arm 27, and therefore secured or fastened to this arm, a relatively small annular wheel or pulley-like member 31. The stud 28 extends centrally through the hub of the member 31 and is riveted thereto. This member is cup-shaped to provide an annular flange or rim 31a about which is wrapped a metallic band or strap 32, preferably in the form of a relatively thin steel tape which is flexible and at the same time substantially inextensible. The tape or band 32 is fastened to the rim 31a by means of a rivet 33 which, as shown in Fig. 4, lies on a diameter of the wheel 31 coincident with the central major axis of the arms 22 and 27 when the window panel is in the half way position. The terminal end of the upper course of the band or tape 32 is fastened by a rivet 34 to a flange portion 16b of the mounting plate 16, and the opposite end of the tape or band is correspondingly riveted at 35 to the flange 16b at a point directly below the point 34. The points 34 and 35 are vertically in line and spaced apart a greater distance than the diameter of annular member 31.

In connection with the embodiment of Figs. 1 to 5 inclusive it will be seen that one end of the mounting plate is formed on a radius having its center at the axis 20 of the driving arm 22. In the present instance the upper and lower parallel embossed portions 16a of the mounting plate are extended around the curved end of the plate, and at this end the metal of the plate is flanged out to provide the arcuate rim or flange 16b having its center at the pivot 20. The ends of the tape 32 are fastened at points 34 and 35 adjacent the opposite ends of the arcuate rim 16b so that when the driving arm 22 swings between the position of Fig. 2 and the position of Fig. 5, during the raising and lowering of the window panel, the upper and lower courses of the tape or band 32 will be alternately wrapped upon or unwrapped from the arcuate rim or flange 16b. As shown in Fig. 2, the lower course of the steel band is partially wrapped upon the surface 16b, and in Fig. 5 the upper course is correspondingly partially wrapped upon this surface while the lower course of the tape or band 32 is unwrapped therefrom.

It will be readily seen that upon rotating the driving gear 18 to swing the arm 22 downward from the position of Fig. 2 to lower the window panel, the positive action of the steel tape 32 will be to partially rotate the drum or pulley member 31 in a counterclockwise direction, thereby swinging the arm 27 downward in the direction of the mounting plate and oppositely to the arm 22. At the half way position of Fig. 4 the arms 27 and 22 extend in parallel overlapping relation, and during further downward movement of the window panel the arm 27 passes by the arm

22 to the position shown in Fig. 5. The reverse action takes place as the window panel is raised and in like manner the balance arm 27 will pass by the arm 22 and also the positive connection 32 between the arm and the mounting plate.

In the present instance the distances between the points 28 and 23 and the points 23 and 29 are equal. Moreover, in the present instance the included angle between the longitudinal center line of the arm 27 and the longitudinal center line of the arm 22 is 60°, and the included angle between the longitudinal center line of the arm 22 and the horizontal line passing through the pivot 20 is 30°. The ratio of these two included angles is 2 to 1, and hence the ratio between the theoretical diameter of the arcuate flange or surface 16b and the diameter of the wheel or drum 31 is also 2 to 1. In the illustrated regulator, therefore, the points of connection 23 and 29 of the arms to the window panel remain at all times in line horizontally and the window panel is positively held at these two spaced points level in all positions thereof and at the same time held against tilting or cocking in the plane of the window panel. Moreover, in the present embodiment it will be seen that the point 29 travels vertically in a straight line path, although the point 23 moves in an arc.

An important feature of the invention resides in the fact that the regulator to a large extent may be used interchangeably as a two arm regulator or a single arm regulator. If used as a single arm regulator the main arm 22 may terminate just beyond the pivot 28.

Referring to the embodiment of Fig. 6 it will be seen in full lines that the main arm 22 terminates substantially at its connection 28 with the arm 27, thus providing a single arm regulator having a single point of connection 29 with the window panel. In dot and dash lines at 22a the arm 22 is extended for connection, as at 23 in Fig. 2, to the window panel providing a two arm window regulator. In the embodiment of Fig. 6 the arcuate surface 16b is omitted and the upper and lower ends of the steel band 32 are attached at fixed points to the extended end 38 of the mounting plate through the medium of projecting pins 36 and 37, the ends of the band having loops embracing the pins in such manner as to permit these ends to turn upon the pins. In this embodiment also the annular member 31 is mounted through stud 28 on the opposite side of arm 22 between the latter and arm 27 and is directly riveted to the latter at 39. Other than this the construction of the regulator in Fig. 6 is substantially identical to the construction shown in Fig. 2.

Thus, as the window panel is lowered or raised the arms 27 and 22 swing in diverging relation and in opposite directions. Since, however, the path of travel of point 29 is non-parallel with respect to the path of travel of point 23, said path of travel of point 29 being either in a

rectilinear path or more nearly approximating one, there is no material tendency of the panel to be shifted laterally to one side or the other by any frictional drag of the stud 23 in the guide 5 slot 24a. Moreover, since arms 27 and 22 swing in opposite directions the points of support 29 and 23 are increasingly separated as the window glass travels down or up toward the half way position, thus achieving a desirable advantage 10 in respect to the stability of the window glass in open position. Also, it will be seen that the entire mechanism is carried by a single support or mounting plate to one side of the center line of the glass and, hence, a remote handle location 15 at 19 may be had. This handle location may be varied, as desired, by variations in the size of gear 18 and in the lengths of arms 22 and 27. It will also be readily seen from the motion 20 of the arms 27 and 22 that too wide a spread of points 29 and 23 is avoided, thus enabling the regulator to be utilized to advantage with both wide and narrow windows.

I claim:

1. A window regulator for raising and lowering a window panel, comprising a mounting plate, a relatively long arm mounted to swing from the plate and having means at its outer end for connection to the panel, a relatively short arm extending entirely to one side of the long arm and pivoted at its inner end thereto, the outer end of the short arm having means for connection to the panel and the short arm adapted to swing oppositely to the long arm and past the same when the panel is raised and lowered, and a flexible member attached to the short arm at a point spaced from the pivot thereof and also at constant vertically spaced points to the plate and effective to hold the short arm against pivotal movement independent of the long arm in any adjusted position of the latter.

2. A window regulator for raising and lowering a window panel, comprising a mounting plate, a main arm mounted to swing from the plate and having driving means at its inner end and means 45 at its outer end for connection to the panel, a second arm extending entirely to one side of the main arm and pivoted at its inner end thereto, the outer end of the second arm having means for connection to the window panel and the second arm adapted to swing oppositely to the main arm and past the same when the panel is raised and lowered, and a flexible member attached to the second arm at a fixed point spaced from the pivot thereof and also at constant vertically spaced points to the mounting plate and effective 50 to hold the second arm against pivotal movement independent of the main arm in any adjusted position of the latter, said vertically spaced points lying on a fixed line substantially parallel to the line of travel of the point of attachment of the second arm to the window panel.

JOHN H. ROETHEL.
